(57) **CLAIM**

The ornamental design for a motorcycle or motorcycle replica as shown and described.

DESCRIPTION

FIG. 1 is a front and left perspective view of a motorcycle or motorcycle replica, showing our new design;
FIG. 2 is a rear and left perspective view thereof;
FIG. 3 is a front and right perspective view thereof;
FIG. 4 is a rear and right perspective view thereof;
FIG. 5 is a left side elevation view thereof;
FIG. 6 is a right side elevation view thereof;
FIG. 7 is a front elevation view thereof;
FIG. 8 is a rear elevation view thereof;
FIG. 9 is a top plan view thereof; and,
FIG. 10 is a bottom plan view thereof.
The broken lines shown in the drawings illustrate portions of the motorcycle or motorcycle replica that form no part of the claimed design.

1 Claim, 10 Drawing Sheets
